Frank M. Ashley

Patented Sept. 25, 1928.

UNITED STATES PATENT OFFICE.

FRANK M. ASHLEY, OF BROOKLYN, NEW YORK.

FOUNTAIN PEN.

Application filed October 29, 1926. Serial No. 144,923.

My invention relates to fountain pens of the self-filling type.

The object of my invention is to provide a self-filling pen in which all of the parts may be made of durable material and which may be filled by a single outward and inward stroke of a piston.

A further object is to provide a pen having a large ink capacity without increasing the usual length of the pen, and other advantages hereinafter set forth.

Referring to the drawings which form a part of this specification:

Fig. 1 is a side elevational view of a pen embodying my design and invention.

Fig. 2 is a longitudinal sectional view of the pen illustrated in Figure 1.

Fig. 3 is an enlarged view of the piston and rod construction shown in Figure 2.

A, indicates the barrel of the pen which is provided with a smooth cylindrical reservoir A', the inner diameter of which is enlarged as illustrated at A². B², indicates the pen section which is shown connected to the barrel by a screw-joint C, but which may be connected by a tight slip joint, or made integral with the barrel if desired.

The pen section is provided with a friction surface at B' reduced in diameter relative to the outer diameter of the barrel A, to provide means for holding the cap B to the pen section, the outside diameter of the cap being made equal to that of the barrel.

This reduction in diameter of the pen section adjacent the barrel, provides a gripping surface for the fingers, of such reduced proportions that a large barrel pen may be provided with a small grip surface, making a very convenient instrument to use, and also presenting a pleasing appearance when the cap is on the pen, the outside of the cap and barrel being of equal diameter.

It will be noted that the pen section is considerably longer than those of pens now in general use, which permits an exceptionally long feed-plug D, to be used, whereby the ink flow may be controlled, which is necessary where a large reservoir is used.

E, indicates a piston of novel construction which I prefer to make of hard vulcanized rubber or other suitable stiff elastic material. The piston E is formed with two or more concentric flanges E' which present sharp outer edge portions which fit closely in air-tight relation with the inner wall of the barrel, and by this construction all sticking of the piston

to the cylinder wall, due to gumming of the ink or undue area of surface contact between the piston and cylinder wall, is eliminated, and the piston may be moved with a minimum of friction and still maintain a perfectly tight sliding joint. I prefer to make the grooves between the flanges E', deep and narrow to permit the flanges to bend slightly, so that there will be an elastic contact between the edges of the flanges and cylinder wall, which provides for wear and also compensates for any unevenness in the cylinder bore. The piston is provided with a longitudinally-extending bore F at its centre, through which extends the piston-rod G on which the piston is rigidly mounted. A valve H is mounted on the end of the piston-rod to close the passage I, leading to the ink-duct in the feed-plug D. An annular space J is formed between the back of the valve and front end of the piston, and in this space mounted on the piston-rod is a disc-shaped valve K, which is free to move back and forth between the valve and piston, and serves to close one or more passages L, when the piston is forced forward in the barrel on its filling stroke.

A plug M, is held by a thread M' to the rear end of the barrel and its outer end is provided with a friction surface M², to engage and hold the cap B. The piston-rod passes through a central bore M³ formed in the plug, and a rod-head R is secured to the outer end of the piston-rod. A stuffing-box is formed in the plug by making a bore N therein to receive packing material N' and a packing nut P, is threaded to engage a thread P', formed in the outer end of the bore. The packing nut P' is screwed into the bore N far enough to provide room for the same thread P', to engage a thread R', formed on the shank R² of the piston-rod head R, to prevent the piston-rod from being accidentally moved, and to regulate the movement of the valve H in controlling the flow of ink to the feed-plug, through the valve seat H', formed in the end of the pen section.

The pen is filled as follows:

First unscrew the head R from the bore N, then submerge the pen point and end of pen section in ink, then draw the piston to the rear end of the barrel, thus causing all air and ink therein to pass through the passages L, to the lower side of the piston, then push the piston downward its full stroke, which will cause the check-valve K to close at the beginning of the stroke, due to a partial vacuum being formed between the inner end of

- the plug M and the piston, and the downward movement of the piston will force all the air and ink that may be in the barrel, into the ink receptacle, and when the piston enters the 5 enlarged bore at A², the atmospheric pressure acting on the surface of the ink in which the pen is submerged, will force the ink through the feed duct and around the piston in the space A² and into the reservoir of the pen, 10 as will be readily understood. When through writing, the valve H may be closed and thus avoid any leakage of ink from the reservoir, and also prevent evaporation in case the pen is laid aside for a considerable period of time. 15 Having thus described my invention, I claim as new:
1. A fountain pen comprising a pen-section, a barrel having a smooth cylindrical bore which is of increased diameter adjacent 20 the inner end of the pen-section, a piston-rod, a piston carried thereby having a passage leading therethrough, and automatic means for opening said passage on the outward stroke of the piston and closing said 25 passage on the inward stroke thereof.
  2. A fountain pen comprising a pen-section, a barrel having a smooth cylindrical bore which is of increased diameter adjacent 30 the inner end of the pen-section, a piston-rod, a piston carried thereby having a passage leading therethrough, and a check-valve for opening said passage on the outward 35 stroke of the piston and closing said passage on the inward stroke thereof.
  3. A fountain pen comprising a pen-section, a barrel having a smooth cylindrical bore which is of increased diameter adjacent 40 the inner end of the pen-section, a piston-rod, a piston carried thereby having a passage leading therethrough, a check-valve mounted directly on the piston-rod for opening said 45 passage on the outward stroke of the piston and closing said passage on the inward stroke thereof.
  4. A fountain pen comprising a pen-section, a barrel having a cylindrical reservoir formed therein, a piston-rod, a piston of hard semi-elastic material mounted rigidly 50 thereon and carried thereby and having a plurality of concentric flanges located directly adjacent to each other with sharp outer edges formed thereon which contact with the 55 walls of the cylindrical reservoir to form an air-tight sliding joint, substantially as set forth.

5. A fountain pen comprising a barrel having a smooth bore, a piston rod, a piston having a passage therethru and fixed on said rod, a means carried by said rod adapted to close said passage on the inward stroke of the piston and open said passage on the outward stroke thereof. 60

6. A fountain pen comprising a barrel having a smooth bore, a piston rod, a piston having a passage therethru and fixed on said rod, 65 and means carried by said rod adapted to close said passage on the inward stroke of the piston and open said passage on the outward stroke thereof, and a valve carried on the inner end of said rod to close the forward 70 end of said barrel.

7. A fountain pen comprising a barrel having a smooth bore, a piston rod, a piston having a passage therethru and fixed on said rod, a check-valve slidably mounted on said rod 75 to close said passage on the inward stroke of the piston and open said passage on the outward stroke thereof.

8. A fountain pen comprising a barrel having a smooth bore, a piston rod, a piston having a passage therethru and fixed on said rod, 80 a check valve slidably mounted on said rod to close said passage on the inward stroke of the piston and open said passage on the outward stroke thereof, and a valve carried 85 on the inner end of said rod to close the forward end of said barrel.

9. A fountain pen comprising a barrel, enlarged in diameter at its forward end to provide a space for ink, and having a smooth 90 bore, a piston rod, a piston having a passage therethru and fixed on said rod, and means carried by said rod adapted to close said passage on the inward stroke of the piston and open said passage on the outward stroke 95 thereof.

10. A fountain pen comprising a barrel having a smooth bore, a piston rod, a piston having a plurality of thin flanges provided with sharp outer edges, said flanges being of 100 slightly larger diameter than the diameter of the bore and adapted to bend slightly to permit the piston to enter the bore and slide in frictional engagement therewith, the said flanges being made of hard semi-elastic material substantially described. 105

In testimony whereof I have affixed my signature.

FRANK M. ASHLEY.
